Primary Examiner — Elizabeth J Oswecki(74) *Attorney, Agent, or Firm* — Au LLC; Adam E. Urbanczyk(57) **CLAIM**

The ornamental design for a diversion safe, as shown and described.

DESCRIPTION

FIG. 1 is a perspective view of a diversion safe showing my new design with an attached and secured separable bottom; FIG. 2 is a side view thereof;

FIG. 3 is a top view thereof;

FIG. 4 is a bottom view thereof;

FIG. 5 is an exploded bottom perspective view thereof;

FIG. 6 is a bottom view thereof, the unsecured bottom is shown in an unattached position; and,

FIG. 7 is a top view thereof, the unsecured bottom is shown in an unattached position.

The cap in FIG. 1, FIG. 2, FIG. 3, FIG. 5 and FIG. 7 are shown in broken lines and form no part of the claimed design.

The interior region in FIG. 5, FIG. 6, and FIG. 7 is shown in broken lines and form no part of the claimed design.
